UNITED STATES PATENT OFFICE.

WILLIAM STUEBING, JR., OF CINCINNATI, OHIO, ASSIGNOR TO THE STUEBING TRUCK COMPANY, OF CINCINNATI, OHIO, A CORPORATION OF OHIO.

LIFTING-TRUCK.

1,381,515.

Specification of Letters Patent. Patented June 14, 1921.

Application filed October 16, 1916. Serial No. 126,014.

To all whom it may concern:

Be it known that I, WILLIAM STUEBING, Jr., a citizen of the United States, residing at the city of Cincinnati, in the county of Hamilton and State of Ohio, have invented certain new and useful Improvements in Lifting-Trucks, of which the following is a specification.

My invention belongs to that class of lifting trucks which are formed of a lower and upper frame, the lower frame mounted on wheels and the upper frame capable of being elevated by means of a lever or handle on the lower frame; also provided with means for locking the upper or elevating frame or platform in its elevated position and means for releasing the elevated platform from its elevated position, so that it may be lowered.

The object of my invention is to incorporate and combine together mechanical parts and movements, that will evolve a lifting truck of this character, which shall be the most simple in construction, the most efficient in use, the most unique and easily operated and the most dependable for constant use.

The front wheels and handle of my new lifting truck are swiveled or pivotally connected and arranged that they may be turned in either direction or entirely revolved around in the arc of a circle or in a complete circle, so that my lifting truck can be operated in any place or under any conditions.

Its various features and advantages will readily become apparent from the following specification.

In the accompanying drawing forming part of this specification,

Figure 1, is a plan view of my new lifting truck,

Fig. 2, is a side elevation of the same,

Fig. 3, is an enlarged view of the forward part of the truck shown in Fig. 2, the mechanism, however, being in a different position.

Fig. 4, is an enlarged view of Fig. 2, partly broken away and in section, to illustrate construction.

Fig. 5, is a similar view to that shown in

Fig. 4, showing the parts and mechanism in a different position,

Fig. 6, is a similar view to that shown in Fig. 3, but taken on the opposite side 55 of the truck,

Fig. 7, is an enlarged plan view of the forward part of the truck,

Fig. 8, is an enlarged view in elevation of the forward part of the truck showing 60 the lifting mechanism disengaged, and locking mechanism disengaged,

Fig. 9, is an enlarged plan view of one of the hooks used by me at forward part 65 of the truck.

Fig. 10, is a front view looking at the truck, and

Fig. 11 is a detail vertical transverse section on line 11—11 of Fig. 7.

The truck is composed of a lower frame 70 mounted on wheels, and an upper frame mounted on said lower frame and capable of being elevated and lowered thereon.

The lower frame is composed of bars or side pieces 1—1 joined at front by means 75 of head 2 and fastened at the bearing points 3 and 4 on both sides; the head 2 extends downwardly and rearwardly as shown in Figs. 1 and 2 and the points 3 and 4 are shown on this extension of the said head 2; 80 and at the rear said bars are joined by the axle 5 and also strengthened at rear by the brace 6 as shown in Figs. 4 and 5. This lower frame is mounted on rear wheels 7 and front wheels 8. On the shaft 5, I place 85 a pair of links 9; these links extend upward and over the rear wheels 7 as shown in Fig. 1. In the upper part of links 9, I connect the shaft 10, which passes through links 9, as shown.

The upper frame is composed of the side bars or rails 12—12 which at rear are connected to the shaft 10, and at front are connected by means of studs 13 and links 14 to the head 2, by means of pins 3 so as 95 to form a pivotal connection. These rails 12—12 are held parallel and in position by cross bar 15 at rear and at front by saddle 16. (see Fig. 1).

In the head 2 I place the bearing 17 100 and in this bearing I swivel or revolve a fork 18. At the lower end of fork 18

(see Fig. 10) I have the bearings 19 and 20, through which I pass the short axle 21.

On the outside of fork 18 and on either side, I mount the front wheels 8 on said axle 21. The bearing 17 in head 2 is so constructed as to permit fork 18 to pass through same.

At the middle of fork 18 I have a shoulder 23 which supports head 2 on fork 18, 10 allowing same to swivel, turn or revolve. At a point 24 in fork 18, I place a pin 25, thus locking the fork in the head 2, at the same time allowing it to revolve freely in bearing 17.

15 In the upper end of fork 18 I carry the bearings 26 and 27 and in said bearings I provide bolt 28 and between said bearings 26 and 27 I place the handle 29 held pivoted in place by the bolt 28. At the lower 20 end of handle 29 I extend two short lugs 30—30 and at its upper end I place a handle bar 31; thus it will be seen that the handle 29 is securely connected to the front wheels and revolves with them and can also be 25 moved up and down at any time, also during the revolution of the wheels.

On the saddle 16, I place the bearings 32 and 33 and between them I place and pivotally connect pawl or hook 34, by means 30 of shaft 35. This pawl 34 is double or U-shaped having two outwardly extending arms or extensions 36 and 37; these arms at their extremity have hook shaped heads 42, as shown in Figs. 3 and 7.

35 On the handle 29, in lugs 30—30, I place the pin 38, which pin extends beyond said lugs 30—30 and these extensions at each side, form engagement bearing points 39, see Figs. 1 and 7, so that when the handle 40 is in an upright position the bearing points 39 will engage the curved hook parts or heads 42 at the end of the arms 36 and 37 of the pawl 34, when pressure is brought on the foot treadle, see Fig. 6, to be here- 45 after described.

On shaft or pin 35 and on the outside of bearing 33, I pivotally connect the small hook 40. This hook has an extending arm 41, (see Fig. 9), which extends in and under the large hook or pawl 34, as shown, and its forward end has a hook part 40', see particularly Fig. 11, which engages hook part on permanent hook 49.

At the opposite side of hook 40 I place 55 an extension 43.

On the head 2 I provide an upwardly extending lug 44 which carries a pin 45 and on this pin I pivotally connect the foot treadle 46, which has a rearwardly extending arm 47 and a forwardly extending arm or foot pad 48. The part 47 extends under the extended portion 43 on hook 40 (see Fig. 7), thus it can be seen that when pressure is put on end 48 of the treadle 46, it 60 will bring extension 47 in engagement with

hook 40 and its extension 43 to raise the large pawl 34 by means of extension 41 on said hook 40 and connect it with the handle as shown in Fig. 6, when the elevating platform is in its lowest position.

At top surface of head 2, I place the holding hook 49, fastened securely to the same and placed in line with the hook 40 (see Figs. 1 and 7); so that, when the elevated platform is in raised position, the small hook 40 engages the holding hook 49 and thus holds the elevated platform in a locked elevated position, (see particularly Fig. 5).

I will now describe a fluid check mechanism which I use in connection with my lifting truck. On the rear side of saddle 16 on the upper platform, I have a lug 50 and at the front side of this brace 6 on lower platform, I have double lugs 51 and 52. Connected to lug 50 I have fork bearing 53, to which piston rod 54 is connected. Between the lugs 51 and 52 I pivotally connect by pin 55 the cylinder 56 closed at its rear end by plug 57 and at its forward end 90 by plug 58, the piston rod 54 passing into cylinder 56 through an opening in plug 58. At the lower end of rod 54, I connect the piston 59 which has any suitable or ordinary valve mechanism connected therewith. Between plug 58 and piston 59, I compress a curved spring 60. The cylinder 56 is filled with liquid, preferably oil, thus causing a checking mechanism governed by the valve in the piston, allowing the elevating platform to lower itself without jar. When it is desired to use the truck it is placed under the object to be elevated and trucked or under a platform made for this purpose onto which the goods to be trucked are piled. After the truck is in its proper position, the handle is now in an upward or upright position and the lifting or elevating platform is in a lowered position as shown in Fig. 2, the operator now steps on the treadle 46, this 100 connects the large hook or pawl 34 with the bearing ends 39 on handle 29 through the medium of the hooked ends or heads 42 of arms 36 and 37 being entered by the said bearing ends 39, (see Fig. 3); the handle 110 is then lowered thus pulling up the elevating platform with its load, until the hook 40 engages the permanent hook 49 on the head 2 (as shown in Fig. 5) thus the elevating platform is locked and held in a 120 locked elevated position. By lifting the handle 29 the pawl 34 is automatically disengaged from said handle, (see Fig. 5); and the front wheels and their supporting frame and the handle can be turned to the 125 right or left in the arc of a circle or completely revolved in a circle.

In order to make the above operation more clear, it may be stated that when it is desired to raise the elevating platform, the 130

operator lifts or raises the handle 29 to a vertical position and at the same time steps on the part 48 of the treadle 46. This operation raises the hook 40, which in turn, through the agency of its arm 41, raises the large pawl 34 by coming in contact with arm 37 of said pawl until the hooked ends or heads 42 of said pawl are engaged by the bearing ends 39 of the handle; the operator with his foot still on the treadle to hold up the pawl 34, then pulls down the handle to force an engagement between said bearing ends 39 and the hooked heads 42 of the pawl (to prevent the pawl 34 from falling away from the bearing ends on the handle), and when this is done he can continue to pull down the handle and elevate the lifting or elevating platform.

When the elevating platform is in a raised position, the links 14 are at right angles to the bottom frame 1, 1, of the truck, that is, on dead center, thus making it easy to lock the load. In order to release the elevated platform when locked and in its highest position and held by hook 40, the treadle 46 is again depressed by the operator; this disconnects said hook 40 from permanent hook 49 on the head 2 (see Fig. 8); this allows the spring 60 in the cylinder 56 to relax therein and either give the lifting platform an initial impetus or pull it down.

This check mechanism is the subject of a separate application and is now pending in the United States Patent Office as Serial No. 90,756.

While I have described one specific form of carrying out my invention, it will be readily understood that the same is capable of change and modification without departure from the principle and spirit of the invention, and I wish to be understood as claiming that such modifications will still fall within the scope of my invention.

What I claim as new and my invention and desire to secure by Letters Patent is:

1. In an elevating truck, in combination, a base, an elevating platform, a front steering wheel having a swivel connection with said base, a steering handle pivoted to rock upon the free upper part of said swivel and having an unlimited range of steering movement, and means for connecting said platform to said handle to elevate said platform comprising a member carried by one of said parts and tending normally to remain in or to return to a position in which it will not interfere with the movement of said handle, the connections between said member and the other part being constituted by co-operating engaging surfaces on said member and said part so arranged with respect to the direction of elevating movement as to form a positive platform elevating connection, and also by co-operating surfaces pre-

venting movement of said member away from connected relation to said part, said last mentioned surface being in such relation to said first mentioned surfaces that movement of the handle in the direction to disengage said first mentioned surfaces also effects relative movement of said last mentioned surfaces out of member-supporting relation.

2. In a lifting truck, a lower frame having forward and rear wheel members, a lifting platform mounted on said lower frame and adapted to be moved up and down with respect thereto, the forward wheel member consisting of a rotatable frame swiveled in said lower frame and carrying the forward wheels, a handle lever, pivoted to said rotatable frame, for raising the lifting platform, a pivoted member on the lifting platform, means on said handle lever for detachable engagement with said pivoted member, a treadle on the forward end of the lower frame, a pivoted hook member on the forward end of the lifting platform, said treadle adapted to be brought into engagement with said pivoted member to raise the same, said pivoted hook member having a portion adapted to be brought into engagement, by the raising of said hook member with the first-named pivoted member when the platform is in lowered position to raise said pivoted member into position to be engaged by said handle lever, a hook on the forward part of the lower frame adapted to be engaged by said pivoted hook member to hold the lifting platform in elevated position, said pivoted hook member adapted to be disengaged from said hook by said treadle to permit the platform to descend.

3. In a lifting truck, the combination with a wheeled base frame and an elevating frame and a pivoted steering handle, of means for connecting said elevating frame to said handle to elevate said elevating frame, comprising a manually operable member connected to one of said parts and tending to move out of connected relation to the other, into a position where it will not interfere with the movement of said handle when used for steering, in combination with treadle and locking means, the treadle means moving said member into position for effecting a connection with said other part and said locking means positively locking the elevating frame to the base frame to prevent descent, before the manually operable member and the other connecting part are disconnected; said treadle means also being capable of releasing said elevating frame from its locked position that the same may descend, said treadle and locking means being independent of the handle.

4. In a lifting truck, the combination with a wheeled base frame and an elevating frame and a pivoted steering handle, of means for

- connecting said elevating frame to said handle to elevate said elevating frame, comprising a manually operable member connected to one of said parts and tending to move out 5 of connected relation to the other, into a position where it will not interfere with the movement of said handle when used for steering, in combination with treadle and locking means, the treadle means moving said member into position for effecting a connection with said other part and said locking means positively locking the elevating frame to the base frame to prevent descent, before the manually operable member 10 and the other connecting part are disconnected; said treadle means also being capable of releasing said elevating frame from its locked position that the same may descend, said treadle and locking means being independent of the handle and of said manually operable member.
5. In a lifting truck, the combination with a wheeled base frame and an elevating frame and a pivoted steering handle, of means for connecting said elevating frame to said handle to elevate said elevating frame, comprising a manually operable member connected to one of said parts and tending to move out 15 of connected relation to the other, into a position where it will not interfere with the movement of said handle when used for steering, in combination with treadle and locking means, the treadle means moving said member into position for effecting a connection with said other part, the movement of the handle in a direction to disconnect said manually operable member and said other part effecting an automatic disconnection therebetween, and the said locking means positively locking the elevating frame to the base frame to prevent descent, before the manually operable member and the other connecting part are disconnected; 20 said treadle means also being capable of releasing said elevating frame from its locked position that the same may descend, said treadle and locking means being independent of the handle and of said manually operable member.
6. In a lifting truck, the combination with a wheeled base frame and an elevating frame and a pivoted steering handle, of means for connecting said elevating frame to said handle to elevate said elevating frame, comprising a manually operable member connected to one of said parts and tending to move out 25 of connected relation to the other, into a position where it will not interfere with the movement of said handle when used for steering, in combination with treadle and locking means, the treadle means moving said member into position for effecting a connection with said other part, the movement of the handle in a direction to disconnect said manually operable member and said other part effecting an automatic disconnection therebetween, and the said locking means positively locking the elevating frame to the base frame to prevent descent, before the manually operable member and the other connecting part are disconnected; 30 said treadle means also being capable of releasing said elevating frame from its locked position that the same may descend, said treadle and locking means being independent of the handle and of said manually operable member.
7. In a lifting truck, the combination with a wheeled base frame and an elevating frame and a pivoted steering handle, of means for connecting said elevating frame to said handle to elevate said elevating frame, comprising a manually operable member connected to one of said parts and tending to move out of connected relation to the other, into a position where it will not interfere with the movement of said handle when used for steering, in combination with treadle and locking means, the treadle means moving said member into position for effecting a connection with said other part and 35 said locking means positively locking the elevating frame to the base frame to prevent descent, said treadle means also being capable of releasing said elevating frame from its locked position that the same may descend, said treadle and locking means being independent of the said manually operable member.
8. In a lifting truck, the combination with a wheeled base frame and an elevating frame and a pivoted steering handle, of means for connecting said elevating frame to said handle to elevate said elevating frame, comprising a manually operable member connected to one of said parts and tending to move out of connected relation to the other, into a position where it will not interfere with the movement of said handle when used for steering, in combination with treadle and locking means, the treadle means moving said member into position for effecting a connection with said other part and 40 said locking means positively locking the elevating frame to the base frame to prevent descent, said treadle means also being capable of releasing said elevating frame from its locked position that the same may descend, said treadle and locking means being independent of the said manually operable member.
9. In a lifting truck, the combination with a wheeled base frame and an elevating frame and a pivoted steering handle, of means for connecting said elevating frame to said handle to elevate said elevating frame, comprising a manually operable member connected to one of said parts and tending to move out of connected relation to the other, into a position where it will not interfere with the movement of said handle when used for steering, in combination with treadle and locking means, the treadle means moving said member into position for effecting a connection with said other part and 45 said locking means positively locking the elevating frame to the base frame to prevent descent, said treadle means also being capable of releasing said elevating frame from its locked position that the same may descend, said treadle and locking means being independent of the said manually operable member.
10. In a lifting truck, the combination with a wheeled base frame and an elevating frame and a pivoted steering handle, of means for connecting said elevating frame to said handle to elevate said elevating frame, comprising a manually operable member connected to one of said parts and tending to move out of connected relation to the other, into a position where it will not interfere with the movement of said handle when used for steering, in combination with treadle and locking means, the treadle means moving said member into position for effecting a connection with said other part, the movement of the handle in a direction to disconnect said manually operable member and said other part effecting an automatic disconnection therebetween, and the said locking means positively locking the elevating frame to the base frame to prevent descent, before the manually operable member and the other connecting part are disconnected; 50 said treadle means also being capable of releasing said elevating frame from its locked position that the same may descend, said treadle and locking means being independent of the handle and of said manually operable member.
